FOREIGN PATENT DOCUMENTS

EP 0867724 9/1998
 EP 1152244 11/2001
 EP 1680225 7/2006

Primary Examiner — Susan Bennett Hattan*Assistant Examiner* — Rebecca Tsehay(74) *Attorney, Agent, or Firm* — Edward J. Baba; Bozicevic, Field & Francis LLP(57) **CLAIM**

The ornamental design for tube rack, as shown and described.

DESCRIPTION

FIG. 1 is a top perspective view of a tube rack;
 FIG. 2 is a bottom perspective view of the tube rack;
 FIG. 3 is a top view of the tube rack;
 FIG. 4 is a bottom view of the tube rack;
 FIG. 5 is a front view of the tube rack;
 FIG. 6 is a back view of the tube rack;
 FIG. 7 is a first side view of the tube rack; and,
 FIG. 8 is a second side view of the tube rack.
 The broken lines in the drawings depict portions of the tube rack that form no part of the claimed design.

1 Claim, 5 Drawing Sheets(56)
